OR D 5,825

UNITED STATES PATENT OFFICE.

ARTHUR M. _____, D, ASSIGNOR TO
HENRY JECKS DIXON & SONS, OF SAME PLACE.

DESIGN FOR A CARPET-PATTERN.

Specification forming part of Design No. 5,825, dated April 30, 1872.

To all whom it may concern:

Specification describing a new and original Design for Carpets, invented by ARTHUR MAZEPPE KING, of Kidderminster, Worcester county, England.

The accompanying photographic illustration fully represents my new design.

This invention relates to a new ornamental design for the main figure of a carpet, said figure being of circular form with decorated border and center, and provided with four projecting palm-leaf shaped projections equidis-

tant from each other. But one such leaf is shown in the photograph, as the same only contains one-fourth of the main figure. A beaded border embraces the leaves and the entire figure.

I claim as my invention—

The design for carpets, as shown.

ARTHUR MAZEPPE KING.
